(57) **CLAIM**

The ornamental design for a handheld printer, as shown and described.

DESCRIPTION

FIG. 1 is a top, front, right-side perspective view of a handheld printer, showing our new design; FIG. 2 is a bottom, rear, right-side perspective view thereof; FIG. 3 is a front view thereof; FIG. 4 is a rear view thereof; FIG. 5 is a right-side view thereof; FIG. 6 is a left-side view thereof; FIG. 7 is a top view thereof; FIG. 8 is a bottom view thereof; and, FIG. 9 is another top, front, right-side perspective view thereof, shown in an environment of use.

The broken lines immediately adjacent to the shaded areas depict the bounds of the claimed design, while all other broken lines are directed to environment. The broken lines form no part of the claimed design.

The black surface shading in FIGS. 1-4 and 7-9 is used to represent the color black or color contrast.
